UNITED STATES PATENT OFFICE.

OTTO J. KUHLKE, OF AKRON, OHIO, ASSIGNOR TO THE AMAZON RUBBER COMPANY,
OF AKRON, OHIO, A CORPORATION OF OHIO.

DESIGN FOR A TIRE-TREAD.

56,619.

Specification for Design. Patented Nov. 16, 1920.

Application filed February 24, 1920. Serial No. 360,995. Term of patent 14 years.

To all whom it may concern:

Be it known that I, OTTO J. KUHLKE, a citizen of the United States, residing at Akron, in the county of Summit and State of Ohio, have invented a new, original, and ornamental Design for a Tire-Tread, of which the following is a specification, reference being had to the accompanying drawing, forming a part thereof.

In said drawing, Figure 1 is a top plan view of a portion of a tire showing my new design, and Fig. 2 is a transverse sectional view of the same.

I claim:

The design for a tire tread substantially as shown.

OTTO J. KUHLKE.
